UNITED STATES PATENT OFFICE.

SILAS F. FAIRBANK, OF BISON, KANSAS, ASSIGNOR OF ONE-HALF TO EDWARD SEHNERT,
OF BISON, KANSAS.

ADJUSTABLE STOVEPIPE.

1,257,071.

Specification of Letters Patent. Patented Feb. 19, 1918.

Application filed November 12, 1917. Serial No. 201,515.

To all whom it may concern:

Be it known that I, SILAS F. FAIRBANK, a citizen of the United States, residing at Bison, in the county of Rush, State of Kansas, have invented certain new and useful Improvements in Adjustable Stovepipes, of which the following is a description, reference being had to the accompanying drawings, forming a part hereof.

10 My invention relates to adjustable stove pipes and has for its object to provide a stove pipe section adapted to be used with stove pipe sections of ordinary construction to vary the length of the stove pipe without 15 the necessity of cutting or fitting, which will be simple and inexpensive to construct, may be readily adjusted to give the length desired and will make tight joints with the ordinary stove pipe sections without liability 20 to leakage.

With these and other objects hereinafter explained in view my invention consists in the construction and combination of elements hereinafter described and claimed.

25 Referring to the drawings:

Figure 1 is a front elevation of my improved adjusting section in position on an ordinary stove pipe section.

30 Fig. 2 is a horizontal sectional view on line 2—2 of Fig. 1.

Fig. 3 is a central longitudinal sectional view of the wedge shaped piece by which the edges of the adjusting section are drawn toward each other and held.

35 Fig. 4 is a perspective view of the wedge shaped piece shown in section in Fig. 3 and

Fig. 5 is a top plan view of the adjusting section.

In the drawings 1 indicates a section of 40 stove pipe of ordinary construction formed in the usual way by bending a sheet of sheet-iron into a cylinder and uniting its edges by the usual joint as indicated at 2 and having near the ends of the cylinder so formed circumferential beads 3 and 4. The section 1 is preferably half the length of an ordinary 45 stove pipe section.

50 5 indicates my improved adjusting section, which is preferably of the same length as the section 1. This comprises a main portion and a wedge shaped piece by which the edges of the main portion are drawn toward each other and held in position. The main portion consists of a sheet of sheet iron

bent into approximately cylindrical form 55 with its adjacent edges inclined slightly to the axis of the cylinder and bent slightly outward as indicated at 6 and then bent inward into hook form as indicated at 7 to engage the edges of a wedge shaped piece 60 or strip 8 which are bent outward into hook form as indicated at 9.

This wedge shaped piece or strip 8 is curved in cross section on an arc of the circle on which the main portion is bent 65 into cylindrical form and is preferably slightly longer than the main portion. The main portion of the adjusting section is provided with a series of circumferential beads 10. In the drawing five of these beads are 70 shown but a greater or less number may be used. These beads are so formed as to fit over the circumferential beads 3 or 4. One end, the upper end as shown in Fig. 1, of the adjusting section is formed as shown at 75 11 to fit into the end of an ordinary stove pipe section, its diameter down to the upper one of the circumferential beads 10 being reduced by the usual longitudinal crimps or corrugations. The hooked edges 7 terminate 80 at this upper one of the circumferential beads so that the upper end portion 11 is free from any obstruction which would interfere with the close fitting of this portion into the end of the stove pipe into which it 85 is inserted. The hooked edges 9 of the strip 8 terminate a distance from the upper end of the strip corresponding to the length of the portion 11 so as to leave a plain end portion 15 adapted to enter the end of the stove 90 pipe section into which the end 11 of the adjusting section is inserted. In order to support this end portion 15 and insure a tight joint the adjacent edges of the portion 11 are depressed inward to form lips 16. 95

In use the wedge shaped piece or strip 8 is moved upward causing the edges of the main portion to separate thus enlarging the diameter of the adjusting section so that the end of the section 1 with its circumferential 100 bead 3 may pass freely into it to such extent as may be necessary to make the combined length of the section 1 and the adjusting section such as may be desired. When so adjusted the circumferential bead 105 3 will be in, or by slight adjustment may be brought into line with one of the circumferential beads 10. When this is done the

wedge shaped piece or strip 7 is moved downward acting upon the edges of the main portion to draw them toward each other and to clamp the bead 3 in the bead 10 and hold 5 the section 1 firmly.

For convenience in shifting the wedge shaped piece or strip 8 its lower end is provided with a tongue 12 narrower than the lower end of the piece or strip 8 so as 10 to pass freely between the lower ends of the edges of the main portion, and this tongue is bent upward and then outward to form a shoulder or hand hold 13, the extreme end of the tongue being bent inward against the 15 body of the piece or strip and riveted or otherwise secured to it as shown at 14.

The adjusting section and the half section shown at 1 are preferably arranged to be furnished to the user together and to form 20 together a length equivalent to that of an ordinary stove pipe section when arranged as shown in Fig. 1 but capable of being shortened to little more than half the length of the ordinary stove pipe section. If less 25 than a half length is required the half section 1 may be discarded and the lower end of the adjusting section slipped over the end of an ordinary stove pipe section.

Having thus described my invention what 30 I claim is:

1. An adjusting section for stove pipes comprising a main portion consisting of a sheet of material bent into approximately cylindrical form with its adjacent edges inclined to the vertical line and bent inward into hook form and having a circumferential bead near one end at such distance from the end as to leave an end portion adapted for 35 insertion into the end of a stove pipe section, and a wedge shaped piece having its edges bent outward into hook form and engaging the inwardly bent edges of the main portion and having at its narrow end an end portion extending beyond the outwardly 40 bent edges and adapted to fit within the end of said stove pipe section, the wedge shaped 45

piece being wholly within the lines of the main portion.

2. An adjusting section for stove pipes comprising a main portion consisting of a sheet of material bent into approximately cylindrical form with its adjacent edges inclined to the vertical line and bent inward into hook form and having a circumferential bead near one end at such distance from the end as to leave an end portion adapted for 50 insertion into the end of a stove pipe section, and a wedge shaped piece having its edges bent outward into hook form and engaging the inwardly bent edges of the main portion 55 and having at its narrow end an end portion extending beyond the outwardly bent edges and adapted to fit within the end of said stove pipe section, the wedge shaped piece being wholly within the lines of the 60 main portion, said main portion having at the end opposite that adapted for insertion into the end of a stove pipe section, a circumferential bead adapted to fit over a corresponding bead on a stove pipe section. 70

3. An adjusting section for stove pipes comprising a main portion consisting of a sheet of material bent into approximately cylindrical form with its adjacent edges inclined to the vertical line and bent inward into hook form and having a circumferential bead near one end at such distance from the end as to leave an end portion adapted for 75 insertion into the end of a stove pipe section, and a wedge shaped piece having its edges 80 bent outward into hook form and engaging the inwardly bent edges of the main portion, and having at its narrow end an end portion extending beyond the outwardly bent edges and adapted to fit within the end of said 85 stove pipe section and having at its broad end a tongue bent upward and outward to form a handle.

In testimony whereof I affix my signature this 29th day of October, 1917.

SILAS F. FAIRBANK.
